METHOD AND APPARATUS FOR PUMPING VOLATILE LIQUIDS

Arthur E. Steele, McKeesport, Pa., assignor to Air Products Incorporated, a corporation of Michigan

Application June 15, 1950, Serial No. 168,190

17 Claims. (Cl. 62—122)

This invention relates to the pumping in liquid phase of liquefied gases and more particularly to the pumping of liquid oxygen or nitrogen.

An important object of the present invention is to provide a method and means for pumping a liquefied gas to a relatively high pressure without gas locking the pump.

Another important object of the invention is to provide a method and means for pumping a liquid product directly from a fractionation column to storage cylinders or pipe lines at a high pressure, thereby avoiding the necessity of a gaseous product compressing system.

A still further object of the invention is to provide a method and means for withdrawing a stream of a liquid product from a fractionating column and for subcooling the product by utilizing a stream of a cold fluid under a higher pressure for pressurizing the product stream.

A still further object of the invention is to provide a method and means for subcooling the propellant stream of fluid before it is utilized to pressurize the stream to be pumped.

A still further object of the invention is to provide a method and means for subcooling a stream of liquid product to be pumped wherein a portion of the pumped fluid is cooled and utilized as the pressurizing stream of fluid to subcool the stream of liquid product to be pumped.

A still further object of the invention is to provide a method and means for starting up the pumping system of the present invention in which a stream of cold fluid, under pressure, from the system is utilized as the pressurizing stream until such time as the pumped fluid can be so utilized.

In the preparation and use of certain liquids having extremely low boiling points at atmospheric pressure, it is often highly economical and desirable to transfer them from one point to another in the liquid rather than in the gaseous condition. It is also common practice to store oxygen, nitrogen and other so-called permanent gases, in the liquefied form, to transport the liquid through pipe lines, and to bring it back to the gaseous condition at the point at which it is to be used or placed in pressure cylinders for final distribution. In such cases the stored liquefied gas is usually at slightly above atmospheric pressure while the conditions of use or distribution may require that the gasified liquid be at a very high pressure, often up to or over 2500 pounds per square inch. In such service, it is extremely desirable to apply the finally required pressure to the liquid rather than to a gaseous stream, as both the cost of power and the weight and complexity of apparatus required in the former case are small fractions of the corresponding figures in the latter.

The step of pumping liquid oxygen or nitrogen has proven in practice to be one of great difficulty. The liquid is, in the nature of the case, at its boiling point at the existing pressure. From this, it follows that any reduction in pressure, such as is occasioned by liquid inertia and friction in the pump suction, or any increase in enthalpy due to heat leakage into the pump body or to

2

frictional heat transmitted into the liquid, will cause the evolution of gas which locks the suction and puts the pump out of commission. A further cause of vapor lock is back leakage through the discharge valve, the high pressure leakage liquid partially flashing to the gaseous state.

It has previously been proposed to prevent the gas locking of the pump by subcooling the liquid stream to be pumped to a temperature below its boiling point at the pressure existing in the pump cylinder during the suction stroke. Various methods of accomplishing the subcooling step have been proposed.

The present invention has solved the problem by a novel method and means whereby a small portion of the pumped liquid under a relatively high pressure is cooled and then injected into the stream flowing to the pump so as to increase the pressure of the stream to be pumped without raising its temperature thereby in effect subcooling the stream.

Referring to the drawings:

Figure 1 is a diagrammatic view of one form of the invention, and

Figure 2 is a similar view of a modified form of the invention.

Referring to the drawings, the system shown in Figure 1 includes a heat interchanger 10 having two banks of tubes 11, 11 and 12, 12 within an outer shell 13 to provide three passageways therethrough in heat exchange relationship with one another. The fractionating column indicated generally by reference numeral 14, is conventional and any preferred form of fractionating column may be used. The form of column disclosed consists of a high pressure section 15 and a low pressure section 16, each supplied with a stack of bubbling plates 17 separated by a partition 18 which includes the conventional downwardly draining condenser 19, the condensate from which drains into the high pressure section of the column. Compressed air enters the interchanger 10 through feed pipe 20, passes through tubes 11, 11 and then through conduit 21 to boiling coil 22 submerged in a pool of boiling crude oxygen 23 in the base of the high pressure section. The air flows from the coil 22 through conduit 24 and expansion valve 25 into the high pressure section of the column at a medial height. In this section of the column, the feed air is fractionated into a substantially pure gaseous nitrogen rising into the condenser 19 which is immersed in a pool of boiling pure oxygen 26 collecting in the base of the low pressure section of the column. As the upper section of the column is maintained at a materially lower pressure than the lower section, the condenser acts as a reboiler for the pure oxygen surrounding it. As a result, the nitrogen rich gas rising in the condenser is liquefied, part falling into the pool 27 and part falling onto the top plate of the lower section 15 where it acts as reflux for the lower section. Liquefied nitrogen from pool 27 is transferred through conduit 28 and expansion valve 29 to the top of the upper section in which it acts as reflux. The crude oxygen product formed in the high pressure section of the column collects in the pool 23 in the base of the column. The crude oxygen collecting in the pool 23 is transferred through conduit 31, 32 and expansion valve 33 to the low pressure stage of the column at a medial height therein.

The high pressure nitrogen stream and the high pressure oxygen stream flowing into the low pressure section of the column are fractionated in the well-known manner to substantially pure oxygen and a slightly impure nitrogen product. The nitrogen product in gaseous form is withdrawn from the top of the low pressure section of the column through conduit 35 and is conducted to the shell of heat exchanger 36 through which it flows in heat exchange relation with the fluid flowing through

coil 37 in heat exchanger 36, to be described hereafter. The nitrogen product stream is then conducted through conduit 38 to the shell of the interchanger 10 where it gives up its cold to the feed air, leaving the interchanger 10 through conduit 39.

The pure oxygen product formed in the low pressure section of the column collects in the pool 26 at the lower end thereof and is withdrawn in liquid form through conduit 41. The oxygen product stream is conducted via conduit 41 to the intake chamber of an injector 42 where a cold stream of liquid under pressure to be described hereafter is injected into the oxygen product stream. The combined streams issuing from the discharge side of injector 42 passes through conduit 43 and is conducted to the suction valve 44 of the liquid pump 45 in which the stream is pumped to the desired pressure. The pump 45 may be any pump capable of handling a liquid at high pressure, but is here illustrated as a single acting plunger pump. Preferably, the pump 45 is similar to that described in Patent No. 2,439,957, dated April 20, 1948, to C. R. Anderson. The prime mover by which power is applied to the pump to reciprocate the plunger is indicated at 46. On the compression stroke of the pump plunger, the liquid oxygen passes through the discharge valve 47, and flows through conduits 48, 49 and control valve 50 to the tubes 12, 12 of interchanger 10, in which the stream is brought to atmospheric temperature and gaseous condition and is discharged through conduit 51 whence it is delivered to pressure cylinders or other pressure vessels (not shown) or to pipe lines in which it is transported under pressure in a gaseous state.

A portion of the pumped liquid oxygen flowing through conduit 48 is diverted at point 52 to conduit 53, control valve 54 and pressure regulator 55 to the coil 37 in exchanger 36. In passing through coil 37 in heat exchange with the colder gaseous nitrogen stream flowing through the shell thereof as previously described, the pumped oxygen stream is cooled to such an extent that flashing into vapor in the injector is prevented. The pressure regulating valve 55 maintains the propellant stream flowing through conduit 56 to the injector 42 at a constant pressure. The propellant stream entering the nozzle of injector 42 is thus a subcooled stream under a relatively high pressure which, by virtue of its velocity component, raises the pressure of the stream to be pumped flowing in conduit 41, without appreciably changing its temperature. The stream flowing from the discharge end of the injector in conduit 43 has a temperature sufficiently lower than its normal boiling point at that pressure so that there will be substantially no flashing of the oxygen into vapor during the subsequent pumping operation.

In starting up the pump, until sufficient discharge pressure has been developed by the pump, a different propellant stream must be utilized. In the embodiment shown in Figure 1, a portion of the crude liquid oxygen flowing in conduit 31 is diverted at point 58 through conduit 59 and control valve 60 to the coil 37 in heat exchanger 36. The crude oxygen stream is there cooled by heat exchange with the gaseous nitrogen stream flowing through the shell of the exchanger to such an extent that it will not flash into vapor in the injector. This subcooled crude oxygen stream under the pressure maintained in the high pressure section of the column is utilized as the propellant stream for the injector until the pump discharge has developed sufficient pressure. During this starting up period, the pump discharge, which is contaminated with the crude oxygen is blown to atmosphere. When sufficient discharge pressure is reached, the control valve 60 is closed and control valve 54 opened to switch to normal operation.

It will be seen that the heat exchanger 36 is utilized for subcooling the propellant stream both during the starting up and during normal operation of the pump.

In the modification of the invention shown in Figure 2, a stream of product oxygen is utilized as the coolant fluid for subcooling the propellant stream. A portion of the high pressure air flowing to the column is utilized as the propellant stream during the starting up period. The operation of the heat interchanger 10, fractionating column 14, injector 42 and pump 45 is identical to that described in connection with Figure 1 and similar reference numerals are used for the corresponding parts.

In this modification, a stream of oxygen product is withdrawn from the low pressure section of the column through conduit 70 and is conducted to the shell of the heat exchanger 36 wherein it flows in heat exchange relation with the propellant stream flowing through the coil 37 therein. The oxygen stream in the shell of the heat exchanger thus acts to cool the propellant stream to a temperature so that it will not flash into vapor in the injector 42. The coolant stream, including vapors evolved from the oxygen due to the heat exchange step, leaves the shell through conduit 71 and is returned to the low pressure section of the fractionating column near the lower end thereof where the vapors are recondensed.

During the starting up of the pump, control valve 54 is closed and a portion of the compressed feed air flowing in conduit 21 is diverted at point 72 therein through conduit 73 and control valve 74 to the coil 37 of heat interchanger 36 where it is subcooled and subsequently utilized as the propellant fluid in injector 42. During the starting up period, the pump discharge which is contaminated with the air is blown to atmosphere. When sufficient discharge pressure is reached, the control valve 54 is opened and control valve 74 is closed to switch to normal operation.

It should be realized that the above embodiments are merely illustrative, and that the use of gaseous nitrogen as the coolant for the propellant stream as shown in Figure 1 could be used in the embodiment of Figure 2, and likewise the use of oxygen product as the coolant as shown in Figure 2 could be substituted for that shown in Figure 1. Likewise, any other colder fluid from the column or an external refrigerant could be used. Similarly, the use of crude oxygen as the starting up propellant fluid for the injector as shown in Figure 1 could be utilized in the embodiment of the invention shown in Figure 2; and likewise, the use of feed air as the propellant as shown in Figure 2 could be substituted for that shown in Figure 1. Again, other fluids from the operation under sufficient pressure, or a cylinder of gas under pressure could be used as the starting up propellant stream. Obviously, where a high pressure stage product is not needed in starting up, the invention is equally applicable to a single stage column.

In the embodiments illustrated, the product being pumped is oxygen, however the systems disclosed will work equally well for pumping other liquid products of the column, such as liquid nitrogen.

It is significant to note also that the proposed schemes are applicable to pumping any volatile liquid from a distillation column, regardless of the temperature level, such as purified natural gas, volatile hydrocarbons from a petroleum distillation column or the like.

I claim:

1. The method of transferring a stream of liquid material from a fractionating operation in which operation a compressed and cooled gaseous mixture is fractionated producing the liquid material as a product, comprising withdrawing a stream of the liquid material from the fractionating operation, passing the stream of liquid material to an ejector, pumping the stream of liquid material issuing from the ejector to the desired pressure, diverting a portion of the pumped stream, effecting a heat exchange between the diverted stream and a stream of colder fluid produced during the fractionating operation to form a subcooled diverted stream, and passing the subcooled diverted stream to the nozzle of the ejector as the propellant stream therefor.

2. In a method for conditioning liquid oxygen product of a fractionating operation for delivery to a receiving means, in which operation compressed and cooled air is fractionated to produce a gaseous nitrogen product and a liquid oxygen product having a temperature corresponding to its boiling point at the pressure present in the fractionating operation, the steps comprising, withdrawing a stream of the liquid oxygen product from the fractionating operation, passing the withdrawn stream of liquid oxygen product to an injector, pumping the stream issuing from the injector to the desired pressure, diverting a portion of the pumped stream, effecting a heat exchange between the diverted stream and a gaseous stream of the nitrogen product, and passing the resulting cooled diverted stream to the nozzle of the injector as the propellant stream therefor.

3. A method of pumping a highly volatile stream of liquid product from a fractionating operation, in which operation a stream of a compressed mixture of low boiling gases is separated into a liquid higher boiling fraction and a gaseous lower boiling fraction comprising, withdrawing a stream of liquid product from the fractionating operation, passing the withdrawn stream of liquid product to an injector, deriving a stream of fluid under relatively high pressure from the stream of compressed mixture of low boiling gases and introducing the stream of fluid into the nozzle of the injector as the propellant stream therefor, pumping the stream issuing from the injector to the desired pressure, diverting a portion of the pumped stream, and substituting the diverted portion of the pumped stream for the stream of fluid under relatively high pressure as the propellant for the injector when the pump discharge has developed sufficient pressure.

4. A method in accordance with claim 3 wherein the propellant streams for the injector are cooled before they reach the injector by heat exchange with a colder product from the fractionation operation.

5. A method in accordance with claim 3 wherein the propellant streams for the injector are cooled before they reach the injector by heat exchange with a stream of gaseous product from the fractionating operation.

6. A method of pumping a highly volatile stream of liquid product from a fractionating operation, in which operation a stream of a compressed mixture of low boiling gases is separated into a liquid higher boiling fraction and a gaseous lower boiling fraction comprising, withdrawing a stream of liquid product from the fractionating operation, passing the withdrawn stream of liquid product to an injector, supplying a portion of the stream of the compressed mixture of gases before separation to the nozzle of the injector as the propellant stream therefor, pumping the stream issuing from the injector to the desired pressure, diverting a portion of the pumped stream, and substituting the diverted portion of the pumped stream for the portion of the compressed mixture of gases as the propellant for the injector when the pump discharge has developed sufficient pressure.

7. A method of pumping a highly volatile stream of liquid product from a fractionation operation, in which operation compressed and cooled air undergoes preliminary rectification in a high pressure stage producing a product enriched in nitrogen and a product enriched in oxygen which are withdrawn and transferred to a relatively low pressure stage for further rectification producing a gaseous nitrogen product and a liquid oxygen product having a temperature corresponding to its boiling point at the low pressure in the low pressure stage, the steps comprising, withdrawing a stream of liquid product from the fractionating operation, passing the withdrawn stream liquid product to an injector, diverting a portion of a product withdrawn from the high pressure stage to the nozzle of the injector as the propellant stream therefor, pumping the stream issuing from the injector to the desired pressure, diverting a portion of the pumped stream, and substituting the diverted portion of the pumped stream for the diverted portion of the product

withdrawn from the high pressure stage as the propellant for the injector when the pump discharge has developed sufficient pressure.

8. A method of pumping a highly volatile stream of liquid product from a fractionation operation, in which operation compressed and cooled air undergoes preliminary rectification in a high pressure stage producing a product enriched in nitrogen and a product enriched in oxygen, which are withdrawn and transferred to a relatively low pressure stage for further rectification producing a gaseous nitrogen product and a liquid oxygen product having a temperature corresponding to its boiling point at the low pressure in the low pressure stage, the steps comprising, withdrawing a stream of liquid product from the fractionating operation, passing the withdrawn stream of liquid product to an injector, diverting a portion of the oxygen rich product withdrawn from the high pressure stage to the nozzle of the injector as the propellant stream therefor, pumping the stream issuing from the injector to the desired pressure, diverting a portion of the pumped stream, and substituting the diverted portion of the oxygen rich product as the propellant for the injector when the pump discharge has developed sufficient pressure.

9. Apparatus for pumping a volatile liquid from a reservoir, in which the liquid is maintained at a pressure corresponding to its boiling point temperature, to a receiving means at a relatively high pressure comprising; a pump having an intake and an outlet for pumping the liquid to the desired pressure; an injector having an intake chamber, a pressurizing nozzle and a discharge side; a first conduit connected to the intake chamber of the injector for supplying liquid from the reservoir to the injector; a second conduit connecting the discharge side of the injector and the inlet of the pump; a third conduit connected to the pressurizing nozzle of the injector for conducting a stream of fluid under a relatively high pressure to the injector, a fourth conduit having a portion in heat exchange relation with a portion of the third conduit, and means for supplying to the fourth conduit a fluid colder than the fluid in the third conduit.

10. Apparatus for pumping a volatile liquid from a reservoir, in which the liquid is maintained at a pressure corresponding to its boiling point temperature, to a receiving means at a relatively high pressure comprising; a pump having an intake and an outlet for pumping the liquid to the desired pressure; an injector having an intake chamber, a pressurizing nozzle and a discharge side; a first conduit connected to the intake chamber of the injector for supplying liquid from the reservoir to the injector; a second conduit connecting the discharge side of the injector and the inlet of the pump; a third conduit connected to the pressurizing nozzle of the injector for conducting a stream of fluid under a relatively high pressure to the injector; a connection between the outlet of the pump and the third conduit for supplying the pumped liquid to the injector as the pressurizing fluid, a fourth conduit having a portion in heat exchange relation with a portion of the third conduit and means for supplying to the fourth conduit a fluid colder than the liquid in the third conduit.

11. Apparatus for pumping a volatile liquid from a fractionating column, in which a fluid is fractionated to produce the volatile liquid as product, to a receiving means at a relatively high pressure comprising; a pump having an intake and an outlet for pumping the liquid to the desired pressure; an injector having an intake chamber, a pressurizing nozzle and a discharge side; a first conduit connected to the intake chamber of the injector for supplying the liquid from the column to the injector; a second conduit connecting the discharge side of the injector and the inlet of the pump; and a third conduit connected to the pressurizing nozzle of the injector for conducting to the injector a stream of the fluid to be fractionated, which fluid is under a relatively high pressure.

12. Apparatus for pumping a volatile liquid from a fractionating column, in which a fluid is fractionated to produce the volatile liquid as a product, to a receiving means at a relatively high pressure comprising, a pump having an intake and outlet for pumping the liquid to the desired pressure; an injector having an intake chamber, a pressurizing nozzle and a discharge side; a first conduit connected to the intake chamber of the injector for supplying the liquid from the column to the injector; a second conduit connecting the discharge side of the injector and the inlet of the pump; a third conduit connected to the pressurizing nozzle of the injector for conducting a stream of fluid under a relatively high pressure to the injector as the pressurizing fluid; a connection between the outlet of the pump and the third conduit for supplying the pumped liquid to the injector as the pressurizing fluid; a fourth conduit for supplying a stream of the fluid to be fractionated, which fluid is under a relatively high pressure; a second connection between the fourth conduit and the third conduit for utilizing the stream of fluid to be fractionated as the pressurizing fluid; and valve means controlling the connections for opening one while closing the other, whereby the fluid to be fractionated can be utilized as the pressurizing fluid in starting up operations.

13. Apparatus as claimed in claim 12 in which a fifth conduit is provided having a portion in heat exchange relation with a portion of the third conduit; and there is means for supplying to the fifth conduit a fluid colder than the fluid in the third conduit.

14. Apparatus for pumping a highly volatile liquid product from a fractionating column, in which compressed and cooled feed air is rectified in two stages maintained respectively at a relatively high and a relatively low pressure, wherein a liquid product enriched in nitrogen and a product enriched in oxygen are produced in the high pressure stage, transferred to a low pressure stage, and a gaseous nitrogen product and a liquid oxygen product having a temperature corresponding to its boiling point at low pressure are produced in a low pressure stage, the combination comprising, a pump having an intake and an outlet for pumping the liquid to the desired pressure; an injector having an intake chamber, a pressurizing nozzle and a discharge side; a first conduit connected to the intake chamber of the injector for supplying liquid oxygen product from the column to the injector; a second conduit connecting the discharge side of the injector and the inlet of the pump; a third conduit connected to the pressurizing nozzle of the injector for conducting a stream of fluid under a relatively high pressure to the injector; a connection between the outlet of the pump and the third conduit for supplying the pumped liquid to the injector as the pressurizing fluid; a fourth conduit for supplying a stream of feed air; a second connection between the fourth conduit and the third conduit for utilizing the stream of feed air as the pressurizing fluid in the nozzle; and valve means controlling the connections for opening one while closing the other, whereby the stream of feed air can be utilized as the pressurizing fluid in starting up operations.

15. Apparatus for pumping a highly volatile liquid product from a fractionating column, in which compressed and cooled feed air is rectified in two stages maintained respectively at a relatively high and a relatively low pres-

sure, wherein a liquid product enriched in nitrogen and a product enriched in oxygen are produced in the high pressure stage, transferred to a low pressure stage, and a gaseous nitrogen product and a liquid oxygen product having a temperature corresponding to its boiling point at low pressure are produced in a low pressure stage, the combination comprising, a pump having an intake and an outlet for pumping the liquid to the desired pressure; an injector having an intake chamber, a pressurizing nozzle and a discharge side; a first conduit connected to the intake chamber of the injector for supplying liquid oxygen product from the column to the injector; a second conduit connecting the discharge side of the injector and the inlet of the pump; a third conduit connected to the pressurizing nozzle of the injector for conducting a stream of fluid under a relatively high pressure to the injector; a connection between the outlet of the pump and the third conduit for supplying the pumped liquid to the injector as the pressurizing fluid; a fourth conduit for supplying a stream of product from the high pressure stage; a second connection between the fourth conduit and the third conduit for utilizing the stream of product from the high pressure stage as the pressurizing fluid in the nozzle; and valve means controlling the connections for opening one while closing the other, whereby the stream of product from the high pressure stage can be utilized as the pressurizing fluid in starting up operations.

16. Apparatus as claimed in claim 15, in which the product from the high pressure stage used as pressurizing fluid in the nozzle is the product enriched in oxygen.

17. Apparatus for pumping a volatile liquid from a fractionating column, in which a fluid is fractionated to produce the volatile liquid as product, to a receiving means at a relatively high pressure comprising; a pump having an intake and an outlet for pumping the liquid to the desired pressure; an injector having an intake chamber, a pressurizing nozzle and a discharge side; a first conduit connected to the intake chamber of the injector for supplying liquid from the column to the injector; a second conduit connecting the discharge side of the injector and the inlet of the pump; and a third conduit connected to the pressurizing nozzle of the injector for conducting a stream of liquid to the injector as the pressurizing stream; a connection between the outlet of the pump and the third conduit for supplying the pumped liquid as the pressurizing liquid; a fourth conduit having a portion in heat exchange relation with a portion of the third conduit; and a fifth conduit for supplying to the fourth conduit a stream of fluid from the column colder than the liquid in the third conduit.
